US00D807198S

(12) **United States Design Patent** (10) **Patent No.:** **US D807,198 S**
Porchia et al. (45) **Date of Patent:** **** Jan. 9, 2018**

(54) **STORAGE BAG**

(71) Applicant: **S.C. Johnson & Son, Inc.**, Racine, WI (US)

(72) Inventors: **Jose Porchia**, Greenfield, WI (US); **Brian C. Dais**, Saginaw, MI (US); **Keegan E. Burggren**, Midland, MI (US); **Imtiaz A. Musaliar**, Racine, WI (US); **Erica Eden Cohen**, New York, NY (US); **Charles P. Althoff**, Brooklyn, NY (US)

(73) Assignee: **S.C. Johnson & Son, Inc.**, Racine, WI (US)

(**) Term: **15 Years**

(21) Appl. No.: **29/600,737**

(22) Filed: **Apr. 14, 2017**

Related U.S. Application Data

(63) Continuation of application No. 29/546,346, filed on Nov. 20, 2015, now Pat. No. Des. 788,599, which is a continuation of application No. 29/510,704, filed on Dec. 2, 2014, now Pat. No. Des. 747,218, which is a continuation of application No. 29/449,559, filed on Mar. 15, 2013, now Pat. No. Des. 724,442, and a continuation of application No. 29/449,579, filed on Mar. 15, 2013, now Pat. No. Des. 723,939, and a continuation of application No. 29/449,596, filed on Mar. 15, 2013, now Pat. No. Des. 723,940, and a continuation of application No. 29/449,633, filed on Mar. 15, 2013, now Pat. No. Des. 724,955, and a continuation of application No. 29/449,652, filed on Mar. 15, 2013, now Pat. No. Des. 742,247, and a continuation of application No. 29/449,674, filed on Mar. 15, 2013, now Pat. No. Des. 723,386, and a continuation of application No. 29/449,687, filed on Mar. 15, 2013, now Pat. No. Des. 723,936, and a continuation of application No. 29/449,706, filed on Mar. 15, 2013, now Pat. No. Des. 723,384, and a

continuation of application No. 29/449,727, filed on Mar. 15, 2013, now Pat. No. Des. 723,937.

CLAIM

The ornamental design for a storage bag, as shown and described.

DESCRIPTION

FIG. 1 is a front view of a storage bag showing our new design;

FIG. 2 is a rear view thereof;

FIG. 3 is a left side view thereof;

FIG. 4 is a right side view thereof;

FIG. 5 is a top view thereof; and,

FIG. 6 is a bottom view thereof.

The shade lines in the figures show transparency or translucency.

The broken lines in the figures show portions of the storage bag that form no part of the claimed design.
